(57) **CLAIM**

The ornamental design for film for packaging production, as
shown and described.

DESCRIPTION

FIG. 1 is a top plan view of a repeating pattern for film for
packaging production; and,
FIG. 2 is a bottom plan view of the film for packaging
production.

The portions of the film within the outer solid line in FIG.
1 are double layers. The film has a minimal thickness, and
the increased thickness of the second layer would not be
clearly distinct in a side view.

The broken lines represent boundaries of the claimed design
and form no part of the claimed design. The dash-dot lines
represent score lines in the film, which are part of the
claimed design.
